CLAIM

The ornamental design for a data communications terminal
for deaf and/or deaf-blind persons, as shown and
described.

DESCRIPTION

FIG. 1 is a top, front, left side perspective view of a data
communications terminal for deaf and/or deaf-blind
persons showing our new design;

FIG. 2 is a right side elevational view thereof;

FIG. 3 is left side elevational view thereof;

FIG. 4 is a front elevational view thereof on an enlarged
scale;

FIG. 5 is a top plan view thereof on an enlarged scale;

FIG. 6 is a rear elevational view thereof on an enlarged
scale;

FIG. 7 is a bottom plan view thereof on an enlarged
scale.
